STATIONARY CAR-TOP MIRROR

Lynn Harold Hodge, Highland Park, Mich.
(12618 Wyoming Ave., Detroit, Mich. 48238)

Filed Aug. 13, 1969, Ser. No. 18,668

Term of patent 3½ years

Int. Cl. D12—16

U.S. Cl. D14—6

FIG. 1 is a full rear view of a stationary car-top mirror showing my new design.

FIG. 2 is a full front view.

FIG. 3 is a cross-section view taken on the line 3—3 of FIG. 4.

FIG. 4 is a plan view.

I claim:

The ornamental design for stationary car-top mirror, substantially as shown.
